US00D715647S

(12) **United States Design Patent**
Jacober et al.

(10) **Patent No.:** **US D715,647 S**
(b4) **Date of Patent:** **** Oct. 21, 2014**

(54) **VENTED END CLOSURE**(71) Applicant: **Ball Corporation**, Broomfield, CO (US)(72) Inventors: **Mark A. Jacober**, Arvada, CO (US);
Howard C. Chasteen, Westminster, CO (US)(73) Assignee: **Ball Corporation**, Broomfield, CO (US)(***) Term: **14 Years**(21) Appl. No.: **29/438,299**(22) Filed: **Nov. 28, 2012**(51) LOC (10) Cl. **09-07**

(52) U.S. Cl.
